Thomas A. Reid.

BY

Wesley G. Barr
ATTORNEY

UNITED STATES PATENT OFFICE.

THOMAS A. REID, OF WILKINSBURG, PENNSYLVANIA, ASSIGNOR TO WESTINGHOUSE ELECTRIC & MANUFACTURING COMPANY, A CORPORATION OF PENNSYLVANIA.

ELECTRIC RESISTOR FURNACE.

Application filed August 28, 1922. Serial No. 584,620.

To all whom it may concern:

Be it known that I, THOMAS A. REID, a citizen of the United States, and a resident of Wilkinsburg, in the county of Allegheny 5 and State of Pennsylvania, have invented a new and useful Improvement in Electric Resistor Furnaces, of which the following is a specification.

My invention relates to furnaces and, 10 particularly, to electrically-heated resistance furnaces.

The object of my invention is to provide a relatively simple resistor mounting for an electrically-heated resistor furnace.

15 In practising my invention, I provide a plurality of refractory heat-insulating walls enclosing a furnace chamber and supporting a plurality of spaced-apart sets of refractory members, of substantially T-shape, 20 projecting into the furnace chamber. The refractory members of T-shape are spaced apart laterally, and relatively thin refractory plates, having grooves in their inner surfaces, are held by the outer ends of the 25 members of T-shape. A relatively heavy resistor member, preformed to comprise a plurality of straight and substantially parallel-extending end-connected convolutions, 30 is held by the grooved plates whereby the convolutions extend substantially parallel to the furnace walls and closely adjacent thereto.

In the single sheet of drawings,

35 Figure 1 is a view, in vertical lateral section, of an electrically-heated pit-type furnace embodying my invention;

Fig. 2 is a fragmentary view, partly in side elevation and partly in longitudinal section, of an electrical-resistance furnace 40 embodying my invention;

Fig. 3 is a top plan view of a refractory supporting member;

Fig. 4 is a view, in side elevation, of the member shown in Fig. 3;

45 Figs. 5 and 6 are top plan and side elevational views, respectively, of a modified form of supporting member;

Figs. 7 and 8 are top plan and side elevational views, respectively, of a still further 50 modification of a supporting member; and

Figs. 9 and 10 are top plan and side elevational views, respectively, of grooved resistor-supporting members employed in the furnace embodying my invention.

55 An electric furnace, designated generally

by the numeral 11, comprises an outer metallic casing 12 of any suitable or desired contour and dimensions. An outer lining 13 is located within the casing 12 and comprises a suitable heat-insulating refractory 60 material constituting side, end and bottom walls. An inner lining 14 is located within the lining 13 and comprises suitable high-temperature resisting refractory material, such as is usually employed in the art. The 65 walls are suitably spaced apart to constitute or enclose a furnace chamber 15 of any suitable or desired contour and dimensions. A muffle lining for the furnace chamber 15 may comprise a plurality of spaced-apart 70 and vertically-extending hollow tile members 16 which alternate with a plurality of refractory bricks or blocks 17 which, in turn, are spaced apart vertically by refractory supporting members 18, of substantially 75 T-shape, the T-end of which extends into the furnace chamber.

Means for supporting a charge to be placed within the furnace chamber 15 may comprise a plurality of suitable refractory 80 members 19 embedded in the bottom linings of the furnace structure.

The furnace structure 11 has an open top which is closed, during the operation of the furnace, by a plurality of cover members 21 and 22. The lower edges of the cover members 21 and 22 rest in masses 23 and 24 of sand which, in turn, are located in members 25 and 26, of substantially channel form in lateral section, located adjacent the outer 90 and the inner edges of the walls of the furnace structure at the top thereof. This construction is more particularly disclosed and claimed in a copending application by G. H. Cole, Serial No. 580,400, filed Aug. 8, 95 1922, and assigned to the Westinghouse Electric & Manufacturing Company, (Case No. 9590).

The members 18, of substantially T-shape, are more particularly illustrated in Figs. 3 100 and 4 of the drawing and, as there shown, are provided with two openings 27 extending laterally therethrough immediately adjacent the end of T-shape. As hereinbefore stated, the members 18 are located in spaced-apart relation in a vertical direction, and relatively thin refractory plates 28, each having a plurality of grooves 29 extending laterally thereof on one surface, are supported by the respective members 18 imme- 110

diately adjacent the wall of the furnace. Instead of grooves and ridges, a plurality of integral projections alined laterally of the plate may be employed, as illustrated in 5 Figs. 9 and 10. The plates 28 are so held that the grooved surface is immediately adjacent to, and faces, the wall of the furnace.

Means for preventing lateral movement of the plates 28 relatively to the supporting 10 members 18 may comprise metal rods 31, of L-shape, which are dropped into the opening 27, the width of the plate 28 being such as to extend substantially between the two members 31 to be held thereby against lateral movement relatively to the supporting members 18.

A resistor member 32 is located in the grooves 29 of the resistor-supporting plates 28 and extends between and beyond these 20 resistor-supporting members and comprises a plurality of straight and substantially parallel-extending end-connected convolutions of a relatively heavy resistor bar which is self-supporting between the resistor-supporting plates 28. No means for making 25 electrical connections with ends of the resistor member 32 is shown, as any suitable or desired construction usually employed in the art may be used. While I have illustrated the heating elements as located in the side and end walls only, the same general 30 construction may be employed in the roof of a furnace.

Figs. 5 and 6 illustrate a modified form 35 of refractory-supporting members of T-shape having only a single opening 27 extending laterally therethrough. The relatively thin resistor-supporting plates 28 employed with this member of T-shape may be 40 provided with a longitudinally-extending groove 33 adjacent to one end thereof within which a portion of the key member 31 may be located, the other portion of the locking or key member 31 being located within the 45 opening 27.

Figs. 7 and 8 illustrate a still further modification of the refractory-supporting members of T-shape, in which a groove 34 extends laterally of the member 18 immediately adjacent to the overhanging flanges of the member. The groove 34 extends from one edge to within a short distance of the other edge of the member, and an opening 27 is located adjacent that edge of the member 18 to which the groove 34 extends. The edges of the plates 28 are located in the grooves 34, and a key or locking member 31 is placed in the opening 27 to prevent lateral movement of the plates 28 in that direction, the shoulder adjacent the other edge of the member 18 preventing lateral movement of the plates in that direction.

In assembling the parts embodied in the 65 furnace structure, the supporting members

of T-shape are located in proper spaced-apart relation, substantially as illustrated in the drawing, and, in mounting the heating element, the preformed resistor member 32 is held against the wall of the furnace, after 70 which the individual plates 28 may be slipped into place back of the overhanging flanges of the members of T-shape adjacent the walls, and facing the same so as to be held thereby. The locking keys 31 may 75 then be placed in position, thus completing the installation of the resistor member.

Various modifications may be made in the device embodying my invention without departing from the spirit and scope thereof, 80 and I desire that only such limitations shall be placed thereon as are imposed by the prior art or are specifically set forth in the appended claims.

I claim as my invention:

1. An electric-resistance furnace comprising a plurality of refractory walls enclosing a furnace chamber, a plurality of longitudinally spaced-apart sets of relatively narrow and laterally spaced-apart refractory supporting members supported by said refractory walls and projecting into said chamber, relatively thin and narrow resistor-supporting plates each having a plurality of laterally extending grooves in one face thereof, a relatively heavy unyielding preformed resistor member supported at spaced intervals by said grooved plates in co-operation with the refractory walls, and means for maintaining said grooved resistor-supporting members in operative engagement with said refractory supporting members.

2. An electric-resistance furnace comprising a plurality of refractory walls enclosing a furnace chamber, a plurality of longitudinally spaced-apart sets of relatively narrow and laterally spaced-apart refractory supporting members supported by said refractory walls and projecting into said chamber, relatively thin and narrow resistor-supporting plates each having a plurality of laterally extending grooves in one face thereof, said grooved supporting members being removable from said supporting members in a plane parallel to the surface of the furnace wall, and means for maintaining said grooved resistor-supporting members in operative engagement with said refractory supporting members.

3. In an electric-resistance furnace, in combination, a plurality of refractory walls enclosing a furnace chamber, a plurality of longitudinally spaced-apart rows of relatively narrow refractory supports of substantially T-shape supported by one of said walls and having the T-end extending into said furnace chamber, said supports being spaced apart vertically in said rows, relatively thin and narrow resistor-supporting

plates extending between, and supported by, jacent the T-end of said refractory supports for preventing lateral movement of 10
said refractory supports of T-shape, each plate having a plurality of grooves in the
face that operatively engages a furnace wall,
5 and a relatively heavy unyielding preformed resistor member having spaced portions thereof resting in said grooves to be supported by said plates, and means located ad-

In testimony whereof, I have hereunto
subscribed my name this 5th day of August
1922.

THOMAS A. REID.
